UNITED STATES PATENT OFFICE.

RAY W. HARROUN, OF INDIANAPOLIS, INDIANA.

INTERNAL-COMBUSTION ENGINE.

1,191,420.

Specification of Letters Patent. Patented July 18, 1916.

Application filed November 25, 1911. Serial No. 662,436.

To all whom it may concern:

Be it known that I, RAY W. HARROUN, a citizen of the United States, residing at Indianapolis, in the county of Marion and State of Indiana, have invented certain new and useful Improvements in Internal-Combustion Engines, of which the following is a specification.

My invention relates to improvements in internal combustion engines, and has among its objects the provision of novel means for control of the supply, admission, and exhaust of working fluid to and from the engine.

More particularly my invention provides a novel and advantageous internal valve construction which is simple, cheap, and efficient, and an association of various sources and means of motive-fluid-supply with each other and with said internal valve structure in new and effective fashion.

In the drawing, wherein I have illustrated an embodiment of my invention; Figure 1 is a schematic view showing the parts of a single cylinder of an engine equipped in accordance with my invention; Fig. 2 is a central vertical cross section of a fragment of an engine cylinder on a plane parallel with the plane of Fig. 1; and Fig. 3 is a central vertical cross section on a plane at right angles to Fig. 2.

In the drawings, 5 indicates in general the engine wherein 6 is the shaft, 7 is the valve shaft geared thereto as by connections 8 for rotation in one to two relation to the engine shaft,—assuming the structure to be a four-cycle engine,—and 9 a cylinder having a head 10 and water jacket 11, 12 being the piston and 13 the clearance space within the engine cylinder between the uppermost position of the piston and the head.

Within the clearance space 13 and the cylinder head 10 I arrange a slide valve 14 providing an annular rim 15 suitably packed as at 16 and mounted on a spider 17 carried by a stem 18, equipped with suitable packing rings 19, extending through a guide aperture in head 10, and in boss 20 depending from said head, the valve being held against rotation by key 21. Exteriortly, the stem 18 is actuated in harmony with the cyclic operations of the engine as by cam 7' upon the cam shaft 7, said cam 7' preferably acting upon a roller 22 in the end of the stem 18, 55 maintained in contact with the cam by the tension of a spring 23, surrounding the stem

and interposed between the head of the engine and a disk 24 carried by the stem. The reciprocating or sliding movement of this valve 15 effects the opening or closing of the ports through which the engine-driving medium is introduced and expelled. In the construction shown, 25 indicates the primary intake port for connection with a source of fuel supply and 26 indicates an exhaust port, non-aligning therewith, these two ports being so located that they both may be simultaneously covered by the valve 15 or either one thereof, alternatively, may be opened thereby. For control of these two ports, the cam is provided with an arcuate "power-stroke" surface 7^a to be referred to; an "exhaust" depression 7^b sufficient to permit the rise of the valve to open exhaust port 26 without opening the inlet 25; an "intake" cam projection 7^c of sufficient height to depress the valve to open intake port 25 without opening the exhaust port 26; and a "compression dwell" surface 7^d locating the valve to close all ports. The intake port may be connected by pipe 25', controlled by throttle 27, with carburetor 28, receiving its gasoline through supply valve 28' and pipe 29' from a gasoline tank 29.

The construction thus far described I believe to be in itself novel and advantageous in many features.

In conjunction with the valve described I preferably arrange for control thereby an entrance passage for an engine-starting medium, such as compressed air, acetylene, or an explosive mixture. In the specific construction shown I make in the head of the machine an intake passage 30 for connection with a source of supply of the starting medium, said passage having a small bore 30' which extends to and communicates with the vertical slideway of the valve stem 18. In said valve stem I form a passageway of conduit 31, comprising an axial portion and two openings to the side of the stem, one of said axial portions being arranged to communicate at times with the conduit 30' while the other thereof opens, preferably constantly, to the clearance space 13 of the cylinder. I prefer that the connections between conduits 30 and 31 be established only while the piston is making its working stroke, with the exhaust port closed, and to this end, I form the "working-stroke" portion 7^a of the cam 7' as a shallow recess sufficiently cut away to permit the slight rise of the valve 15 above

the compression position, sufficient to bring conduits 30 and 31 into register.

As a simple illustration of a suitable construction for supplying a starting fluid—
5 say compressed air—to the conduit 30, I illustrate a pipe 32 leading from said conduit 30 through a check valve 33 to a pressure tank 34, there being a by-pass 35 provided around the check valve 33 controlled
0 by a manually operable valve 36.

It is sometimes desirable to employ in an engine relatively heavy oil, which may be advantageously heated and vaporized in the course of its introduction into the cylinder;
5 and for meeting such requirements in an engine employing a valve as heretofore described, I make provision as follows: 40 indicates an oil chamber in the head of the engine having an oil inlet 41 and a port 42 leading to the slideway of valve stem 19. In the valve stem is made a transverse pocket or bore 43, preferably arranged in such position as to register with the port 42 while portion 7^a of the cam causes a dwell in the 20 operation of the valve, thereby to enable the bore or pocket to fill with oil during the course of each reciprocation of the valve. At such low position in the boss 20 that bore 43 may register therewith when the 25 valve is depressed by cam portion 7^a, I provide a transverse passage 45 having one end connected as by a piping coil 46, and coupling 47, with an air inlet 48 in the head of the engine. Thus the small body of oil 30 trapped in the pocket 43 is brought down, at the time of each suction stroke of the engine, to register with the passage 45, and the rarefaction within the engine cylinder on the suction stroke causes air to flow 35 through the inlet 48 and the tube 46 (thereby becoming heated) to expel the small body of oil from the bore 43 to the cylinder in the form of a heated spray or vapor.

The port 42 for the heavy oil may be 45 suitably controlled as by a needle valve 50, having a threaded portion 51 adjustably mounted in a carrier 52 threaded with a rapid thread into the side of the cylinder, and provided with a handle 53 for adjustment. Where the heavy oil supply is employed, I prefer that the same shall be introduced from a supply tank 55 into the head to be heated through the agency of pump 56, geared as at 57 to the engine, so that the pump-generated pressure will vary with the speed of the engine, said pump having piping connections 68 containing a pressure gage 69 to the head opening 41. A by-pass 70 from the pipe 68, back to the oil tank, may be provided controlled by an adjustable spring check valve 71, so as to limit the pressure which can be applied to the head.

In the cycle of operations of the cam in 65 the direction shown by the arrow in Fig. 3,

on the power stroke passage 30—31 is opened, and ports 25 and 26 closed; on the succeeding exhausting stroke, while cam portion 7^b is in effective position, the exhaust 26 is opened and intake port 25 closed; 70 then while cam part 7^c acts on the intake stroke, intake port 25 is opened and port 26 and passage 30—31 closed; and on the compression-stroke, while arc 7^d is acting, all of the ports are closed.

For simplicity I have herein shown a single cylinder of an engine, but it will be understood that gas engines are commonly built with a plurality of cylinders in such a crank relation that one or more thereof 80 stands always with its piston on the working stroke, wherever the engine may be stopped. To start an engine therefore, it is only necessary to turn pressure from tank 34 into the engine head passage 30 by the operation of the valve 36, the starting medium entering the cylinder through the communicating passage 30—31 to start the piston in operation. Even where heavy oil is to be used as the final medium for combustion, the engine may well be run for a short time on gasoline until it is properly heated up. To this end, the gasoline valve 28' and the throttle 27 are properly set, and the engine, started as described, will run as an ordinary gasoline engine, the intake and exhaust ports being opened in proper succession by the valve 15 and the passage 30—31 best to the pressure tank 34 being opened during each working stroke of the engine, so that the pressure in said tank is automatically brought back to normal. When the engine is properly heated up so that the oil content of the head 15 is in proper condition for utilization, the gasoline valve 28' may be closed, and the oil valve 50 be opened, so that oil will be trapped into the cylinder through the medium of the pocket 43, and atomized by a secondary air current entering through the passage 46—48, the main air supply entering through pipe 25'. While I have herein described in some detail a particular embodiment of my invention, it will be understood that changes in the construction and arrangement thereof might be made without departure from the spirit of my invention and within the scope of the appended claims, and that some of the features described and claimed may be used separately with retention of parts of the advantages heretofore described.

What I claim is:

1. In an internal combustion engine, the combination of a cylinder having in its side walls fuel inlet and exhaust ports, in different transverse planes; a valve rim, imperforate and of a depth to span and close both ports, coöperating therewith that by movement to three positions its opposite edges may respectively lie between the planes of

the ports to open said ports respectively or may span both ports to close them simultaneously; a series of spider arms within said rim; a stem extending centrally from the spider through a guiding orifice in the head of the cylinder; a spring surrounding said stem, acting at opposite ends against the cylinder and the stem; and a cam acting on the extremity of said stem to move the valve against the resistance of said spring.

2. In an internal combustion engine, the combination of a cylinder; a piston therein arranged to leave a clearance space in the end of the cylinder, there being intake and exhaust ports opening to said clearance space, a valve in said clearance space comprising a head and a stem, the head coöperating with said intake and exhaust ports to open and close the same, and means for reciprocating said valve and stem, there being in said valve stem and the coöperating cylinder portions a stem passage and a cylinder port arranged to be brought into register while the valve head maintains its coöperating ports closed.

3. In an engine, the combination of a cylinder, a piston therein arranged to leave a clearance space in the end of the cylinder, a valve in said clearance space comprising a head and a stem, means for reciprocating said valve and stem in appropriate timed relation to the reciprocations of the pistons, there being inlet and outlet ports to the clearance space controlled by the valve head and there being a passage to be opened during the working stroke of the engine from said clearance space to the exterior of the engine, said passage being controlled by said valve.

4. In a four-cycle engine, the combination of a cylinder having three ports for communication with its clearance space, one said port adapted to be associated with a source of supply of fluid under pressure, another of said ports being adapted for association with a source of fuel supply, and the third said port being adapted and arranged to act as an exhaust port, a piston, a single valve structure, and means for moving said single valve structure successively to four positions during the four succeeding cycles of the engine, three of said positions to open the three ports respectively and the fourth position to close all of the ports, whereby said ports are successively opened for starting and running of the engine, and means for cutting off the first said port from its source of fluid supply after starting of the engine.

5. In an engine, the combination of a cylinder, a piston therein, a cylindrical slide valve arranged in the clearance space between the piston and cylinder, having its sides coöperating with the walls of the clearance space, there being in the cylinder

structure ports controlled by said valve, adapted to be opened one during the power stroke of the piston to permit the introduction of starting fluids, and others during the suction and exhaust strokes of the piston to permit the ingress and egress of fuel and gases, respectively, and means to reciprocate said valve within said clearance space in timed relation to the operations of the piston to secure the stated openings of the ports.

6. In an engine, the combination of a cylinder having an exhaust port opening to its clearance space, a slide valve in said cylinder having a rim coöperating with said port and a stem extending through the cylinder head, means for reciprocating said valve stem in timed relation to the cyclic operations of the engine, there being an air passage to the clearance space and a port in the stem arranged when in one position to open said air passage, and means to supply fuel to said stem port when the valve is in another position, thereby to trap fuel into said air passage.

7. In an engine, the combination of a cylinder having an exhaust port opening to its clearance space, a valve in said cylinder having a rim coöperating with said port, and a stem extending through the cylinder head, means for reciprocating said valve stem in timed relation to the cyclic operations of the engine, a piping coil within the clearance space of the cylinder having an end opening controlled by said valve-stem, there being an aperture in the stem arranged when in one position to open said end of said piping coil, and means to supply fuel to said stem-aperture when the valve is in another position.

8. In an engine, the combination of a cylinder having an exhaust port opening to its clearance space, a valve in said cylinder having a rim coöperating with said port, and a stem extending through the cylinder head, means for reciprocating said valve stem in timed relation to the cyclic operations of the engine, there being an air passage to the clearance space controlled by said stem and an aperture in said stem arranged when in one position to open said air passage, and a fuel reservoir in the engine head with which said aperture in said stem communicates when the stem is in another position.

9. In an internal combustion engine, the combination of a cylinder having in its side wall an exhaust port, a valve rim imperforate and of a depth sufficient to cover said port, coöperating therewith; a series of spider arms within said rim, a stem extending centrally from the spider through a guiding orifice in the head of the cylinder, a fuel supply port communicating with the opening through which said stem passes, said stem containing a bore movable to communi-

- cate with the fuel port and also out of communication with said port to carry its entrapped fuel, an air duct opening at one end extraneously to the cylinder and at its other end arranged for communication, through said movable bore when the latter is in its last mentioned position, and cam means for imparting movement to said stem in a cyclic order.
10. 10. In an internal combustion engine, structure providing in conjunction with a cylindrical wall, a fuel supply port, an air duct having adequate exposure to the engine cylinder for heating of its contents, and one end opening extraneously to the cylinder, a movable trapping means associated with said structure, in one position to communicate with the fuel supply port and in another position to establish communication from the exterior of the cylinder through said air passage to the clearance space, a piston in said cylinder, and means timed with respect to the movements of said piston for moving said movable part, arranged to effect the stated communication between said trapping part and the exterior of the cylinder.
15. 15. In an internal combustion engine, structure providing in conjunction with a cylindrical wall, a fuel supply port, an air duct having adequate exposure to the engine cylinder for heating of its contents, and one end opening extraneously to the cylinder, a movable trapping means associated with said structure, in one position to communicate with the fuel supply port and in another position to establish communication from the exterior of the cylinder through said air passage to the clearance space, a piston in said cylinder, and means timed with respect to the movements of said piston for moving said movable part, arranged to effect the stated communication between said trapping part and the exterior of the cylinder.
20. 20. In an internal combustion engine, structure providing in conjunction with a cylindrical wall, a fuel supply port, an air duct having adequate exposure to the engine cylinder for heating of its contents, and one end opening extraneously to the cylinder, a movable trapping means associated with said structure, in one position to communicate with the fuel supply port and in another position to establish communication from the exterior of the cylinder through said air passage to the clearance space, a piston in said cylinder, and means timed with respect to the movements of said piston for moving said movable part, arranged to effect the stated communication between said trapping part and the exterior of the cylinder.
25. 25. In an internal combustion engine, structure providing in conjunction with a cylindrical wall, a fuel supply port, an air duct having adequate exposure to the engine cylinder for heating of its contents, and one end opening extraneously to the cylinder, a movable trapping means associated with said structure, in one position to communicate with the fuel supply port and in another position to establish communication from the exterior of the cylinder through said air passage to the clearance space, a piston in said cylinder, and means timed with respect to the movements of said piston for moving said movable part, arranged to effect the stated communication between said trapping part and the exterior of the cylinder.

ping part and the air duct during the suction stroke of the piston.

11. In an internal combustion engine, structure providing in conjunction with a cylinder wall, a fuel supply port, an air duct 30 having one end communicating to the atmosphere, a movable trapping means associated with said structure, in one position to communicate with the fuel supply port and in another position to establish communication 35 from the atmosphere through said air passage to the clearance space, a piston in said cylinder, and means timed with respect to the movement of said piston for moving said movable part, arranged to effect the stated 40 communication between said trapping part and the air duct during the section stroke of the piston.

In testimony whereof I hereunto set my hand in the presence of two witnesses.

RAY W. HARROUN.

In the presence of—

W. GUSTAVE POLACK,

W. M. YOUNG.
